UNITED STATES PATENT OFFICE

2,498,447

CIRCULAR KNITTING MACHINE

Charles Willin Perkins, Leicester, England

Application October 1, 1948, Serial No. 52,391
In Great Britain September 12, 1947

11 Claims. (Cl. 66—56)

1.

This invention relates to circular knitting machines, and is more particularly concerned with machines of the superposed cylinder type.

Such machines are usually provided with driving mechanism by which the needle cylinder can either operate in a continuous rotary manner or alternatively in a reciprocatory manner. The continuous rotary movement produces the plain tubular work, and the reciprocatory movement enables enlarged pockets, such as the heel portions of hosiery, to be formed.

The object of this invention is to provide improved means for changing over from rotary to reciprocatory movement.

Referring to the drawings which form a part of this specification:

Figures 1 and 2 are sectional elevations on the line I—I of Figure 3 showing two alternative positions of the mechanism.

Figure 3 is a sectional elevation in a plane at right angles to Figures 1 and 2.

Figure 4 is a plan.

A shaft 10 has a clutch mechanism comprising a central slidable body member 11 with male dogs 12, 12^a at each end and two female parts 13, 13^b with either of which the body member 11 can engage by virtue of sliding movement. The body member 11 is slidably axially on splines on the shaft 10 and rotates therewith. The shaft 10 may be the main center shaft of the knitting machine or (preferably) another shaft geared with the main shaft. The shaft 10 is provided with a bevel gear (not shown) which, in turn, meshes with a bevel gear on the cylinder (not shown). In one position of the mechanism, as shown in Figure 1, the sliding body member 11 is coupled to the female part 13 and a gear wheel 14. This gear wheel is the driving element from which rotary movement of the needle cylinder is produced. In the other position of the mechanism, as shown in Figure 2, the sliding body member 11 is coupled to the female part 13^b and a pinion 15. The pinion 15 is driven by the quadrant which is the driving element from which reciprocatory motion of the needle cylinder is produced. The gear wheel 14 is freely rotatable on the shaft 10 but is fixed against axial movement on the shaft by means of a sleeve-like element 14A carried by the shaft 10. The pinion 15 is similarly mounted on the shaft 10, although the sleeve-like element is not illustrated in the drawings.

Around the body member 11 a cam mechanism is fitted. This is shown as a ring cam consisting of two separately adjustable profile members 16, 16^a. One end of a rocking lever 17 engages with

the cam, for instance the end of the lever 17 may carry a roller 18 or fixed member which rides on the cam profiles. There is a gap 19 in the cam profiles 16, 16^a. When the lever 17 is rocked the end of the lever can pass through this gap 19, so that the lever will then be engaged by the opposite cam profile. The lever is shaped somewhat like a bell-crank. The opposite end 17^a of the lever extends into a gap 20 between a pair of set screws 21, by which the amount of rocking movement imparted to the lever in either direction can be adjusted as required. The rocking movement of the lever 17 is derived from a cam 22 carried by the pattern drum PD of the knitting machine. The cam 22 acts on a roller 23 carried by a plate 17^b freely mounted on the same axis as the lever 17. This pre-loads or conditions the lever against the action of a spring 25 anchored to the members 17, 17^b. The roller 18 is thus caused to bear against the cam profile 16^a until the gap 19 comes round. The roller 18 then passes through the gap, as the lever 17 rocks about its pivot 24, and presently the roller bears against the slope or rise of the other cam profile 16. Since the profiles 25 are fixed to the body 11 and since the lever 17 is held in position, the result is that the clutch body is moved slidably. When the roller 23 comes off the cam 22 the spring 26 anchored to the lever 17 and to the frame becomes operative, so that the lever 17 will move back through the gap 19 in the cam profiles 16, 16^a and engage with the opposite profile. Presently the slope or peak on this face becomes operative and the cam profiles and clutch body 11 are thereupon moved slidably in the reverse direction. The movement of the plate 17^b under the action of the spring 25 is limited by a peg or stop 27.

I claim:

1. A mechanism for a circular knitting machine of the cylinder type including a clutch member mounted for sliding movement, said clutch member being adapted in one position to actuate means by which continuous rotary movement of the needle cylinder is effected, and in the other position to actuate means by which reciprocatory movement of the needle cylinder is effected, cam means carried by the clutch member, a lever operatively associated with the cam means, and means for conditioning the lever, said lever in conjunction with said cam means being adapted to impart sliding movement to the clutch member.

2. A mechanism for a circular knitting machine of the cylinder type comprising a cam associated with the pattern drum of the knitting

machine, a lever operatively associated with said cam, a sliding clutch member, said clutch member being adapted by its sliding movement to change the needle cylinder from rotary to reciprocatory movement or the reverse, cam means carried by the clutch member, and spring means associated with the lever, said spring means serving to urge said lever against said cam means on the clutch member.

3. A mechanism as claimed in claim 1 having in addition the feature that the lever is pre-loaded by spring means associated therewith.

4. A mechanism as claimed in claim 1 in which the cam means on the clutch member comprises two separate profiles with each of which the lever engages in turn.

5. A mechanism as claimed in claim 1 in which the cam means on the clutch member comprises two separately adjustable profiles with each of which the lever engages in turn.

6. A mechanism as claimed in claim 1 in which the cam means on the clutch member comprises two profiles with a gap between them, said lever being adapted to move through the gap when it is actuated.

7. A mechanism as claimed in claim 1 having in addition the feature that a part of the lever extends into a clearance between a pair of abutments, the abutments being adjustable to alter the clearance, so that by altering the setting of the abutments the limit of movement of the lever in either direction is adjusted.

8. A mechanism as claimed in claim 1 in which the lever is actuated by a cam carried by the pattern drum of the knitting machine, said cam engaging with one end region of the lever, while the other end region of the lever carries a roller which rides on the cam means on the clutch member.

9. A mechanism for a circular knitting machine of the cylinder type including a clutch member having male parts at each end, two female parts with either of which the clutch member can engage, one associated with means for effecting continuous rotary movement of the needle cylinder of the machine and the other with means for effecting reciprocatory movement of said needle

cylinder, two cam profiles on said clutch member, a lever engaging with said profiles, there being a gap through which said lever can move from one cam profile to the other, and means associated with the pattern drum of the knitting machine for conditioning said lever, whereby said lever in conjunction with the cam profiles acts to move the clutch member slidably from engagement with one female part to the other.

10. A mechanism for a circular knitting machine of the cylinder type comprising a cam associated with the pattern drum of the machine, a pivoted lever and a plate freely mounted on the same axis, a spring connected between the lever and the plate, the action of the cam serving to spring-load the lever, two cam profiles engaged by said lever, a sliding clutch member associated with the cam profiles, a gap through which the lever can move from engagement with one cam profile to engagement with the other, another spring connected to the lever, said further spring becoming active on said lever when the cam on the pattern drum ceases to be effective, whereby the lever is oppositely spring-loaded, the lever in conjunction with the cam profiles serving to move the clutch member slidably, said clutch member being adapted in one position to be associated with means for effecting continuous rotary movement of the needle cylinder and in the other position to be associated with means for effecting reciprocatory movement of the needle cylinder.

11. A mechanism as claimed in claim 10 in which adjustable means are provided for limiting the amount of movement imparted to the lever in either direction.

CHARLES WILLIN PERKINS.
